CLAIM

The ornamental design for an agitator bead mill, as shown and described.

DESCRIPTION

FIG. 1 is a front left isometric view of an agitator bead mill in accordance with the new design;

FIG. 2 is a front right isometric view thereof;

FIG. 3 is a rear right isometric view thereof;

FIG. 4 is a rear left isometric view thereof;

FIG. 5 is a right side elevational view thereof;

FIG. 6 is a left side elevational view thereof;

FIG. 7 is a front elevational view thereof;

FIG. 8 is a rear elevational view thereof;

FIG. 9 is a top plan view thereof; and,

FIG. 10 is a bottom plan view thereof.

The broken lines show portions of an agitator bead mill that form no part of the claimed design.

1 Claim, 10 Drawing Sheets
